UNITED STATES PATENT OFFICE.

PAUL SERENE, OF YOUNGSTOWN, OHIO, ASSIGNOR OF ONE-THIRD TO L. F. DONNELL
AND ONE-THIRD TO B. P. HIGBY, BOTH OF YOUNGSTOWN, OHIO.

POWER-OPERATED RAZOR.

Application filed March 4, 1922. Serial No. 540,954.

To all whom it may concern:

Be it known that I, PAUL SERENE, a citizen of the United States, and a resident of Youngstown, county of Mahoning, and 5 State of Ohio, have invented a new and useful Improvement in Power-Operated Razors, of which the following is a specification, the principle of the invention being herein explained and the best mode in 10 which I have contemplated applying that principle, so as to distinguish it from other inventions.

The present invention relates to a power driven razor in which provision is made for 15 reciprocating the blade vertically, that is, at a right angle to the edge of the blade of the razor, and further provision is made for enclosing the operating means and the blade in a suitable housing in such a manner that 20 the finished razor will be small and compact and readily usable by a barber or other person. This razor is particularly adapted for use by barbers being of the straight blade type rather than the hoe type of razor. To 25 the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used. 30

35 In said annexed drawing:—

Fig. 1 is a side elevational view of the device showing the comparative size of the same; Fig. 2 is an enlarged side elevational view of the razor; Fig. 3 is a longitudinal 40 section through the razor showing the driving mechanism; Fig. 4 is a sectional view on the line 4—4 of Fig. 3; and Fig. 5 is a sectional view similar to Fig. 4 but showing the driving mechanism in a different position. 45

The present razor is of the usual straight blade type having a handle 1 which is provided with an aperture or bore 2 to receive the rotatable driving shaft 3, this shaft being connected at the outer end of a suitable 50 flexible drive shaft 4 adapted to be driven from any source of power. This razor handle has an extended end 5 which carries the blade and operating mechanism and the

housing for the same. The housing consists 55 of two members 6 and 7 which have complementary engaging portions 8 at the top which are apertured to receive a pin or rod 9 to secure the two members together and to the handle. The members are bulged at 60 their upper portion to form a substantially cylindrical chamber 10 which leads into an elongated vertical chamber 11 toward the bottom of the razor and the two members are spaced apart sufficiently to leave an 65 elongated slot 12 for the razor blade 13 proper. Attached to one member 7 is a guard member 14 which is provided with a shoulder 15 at its upper portion adapted to fit snugly against a complementary 70 shoulder 16 on the housing member 7 to which it is attached by means of a screw 17 engaging in suitable threaded apertures in the housing member and the guard. The guard extends below the edge of the razor 75 blade and at the lower end is provided with a series of teeth 18 having cylindrical guard points 19 at the bottom so as to act as a safety guard for the razor blade proper.

The driving mechanism consists essentially 80 of a shaft or crank 20 which is eccentrically attached to a cylindrical portion 21 which is provided with a centrally threaded aperture 22 adapted to be engaged with the driving shaft 3 and this cylindrical portion is in 85 the housing. At the outer end of the handle is mounted another cylindrical portion 23 which is carried in a bearing in the front end of the housing and this cylindrical member has a spherical end 24 which is held 90 in position by means of a set-screw 25 having a concave end 26 acting as a thrust bearing for the end of the cylindrical portion. Thus the shaft 3 has a crank action and this shaft carries a tube 27 having a downwardly extending flange 28 ending in a series of cylindrical teeth 30 which are provided with aligned apertures 31. The razor blade has at its upper edge a complementary 95 series of cylindrical teeth 32 with aligned apertures 33, the teeth fitting snugly between the teeth on the driving tube. To secure the blade to this driving tube, a rod 34 is passed through the aligned apertures, thus securing the blade to the tube but allowing the blade to rock relatively to the tube in order to allow the blade to have a vertical motion while the tube has not only 100

105

a vertical but also a rocking motion. These cylindrical teeth fit within the elongated slot within the housing which forms a guideway and thus gives the blade a reciprocating motion as the driving tube is carried around by means of the eccentric shaft or crank.

The present razor, as shown in Fig. 1, presents approximately actual size, while the other figures are considerably enlarged in order to better show the actual operating mechanism. In a razor of this type it is necessary to maintain the size close to the limits in size of the ordinary straight bladed razor and the present razor is adapted to be made with a blade length not exceeding three inches, and with a total depth of approximately one and one-half to three-quarters of an inch. In this way the length of stroke of the blade may be kept within very small limits, and the blade stroke is preferably not to exceed one-sixteenth of an inch and may even be less. The blade should be reciprocated very rapidly and thus as the razor is drawn over the face, the reciprocation of the blade cuts the hairs and the necessary transverse action is obtained by the movement of the razor as a whole instead of by any longitudinal movement of the blade. As previously stated, this type of razor is particularly adaptable for use by barbers or others who shave individuals, as the hoe-type of razor cannot be satisfactorily used by one person in shaving another. While the guard is not necessary, it aids in allowing the barber to properly angle the razor to the face and also aids in the safety of the razor.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a power operated razor, the combination of a handle having a longitudinal aperture, a two part hinged housing connected to said handle, an eccentric driving crank mounted in said housing, a rotatable driving shaft in said handle operatively connected to said crank to rotate the latter, a driving tube mounted on said crank in said housing, a blade hinged to said tube and extending outwardly between said housing members and adapted to be reciprocated at right angles to the blade by reciprocation of said driving tube.

2. In a power operated razor, the combination of a housing comprising two members hinged together at the top and forming a hollow casing, a handle attached to said housing, said handle being provided with

a longitudinal aperture, a driving shaft rotatably mounted in said handle, an eccentric driving crank mounted in said housing and operatively connected to said drive shaft, a driving tube rotatably mounted on said crank and having a driving flange extending downwardly in said housing, a razor blade reciprocably mounted between said two housing members and pivotally attached to said driving flange to be reciprocated thereby upon rotation of said crank.

3. In a power operated razor, the combination of a housing comprising two members hinged together at the top and forming a hollow casing, a handle attached to said housing, said handle being provided with a longitudinal aperture, a driving shaft rotatably mounted in said handle, an eccentric driving crank mounted in said housing and operatively connected to said drive shaft, a driving tube rotatably mounted on said crank and having a driving flange extending downwardly in said housing, a razor blade reciprocably mounted between said two housing members and pivotally attached to said driving flange to be reciprocated thereby upon rotation of said crank, and a guard member having teeth at its lower edge attached to one of said housing members and extending below the edge of said razor blade.

4. In a power operated razor, the combination of a housing comprising two bulged members hinged together at the top to form a hollow casing having a longitudinal cylindrical chamber and an elongated chamber, said two members being spaced apart at their lower edge to form a narrow slot, a handle attached to said casing and having a longitudinal aperture in alignment with such cylindrical chamber, a driving shaft rotatably mounted in such handle aperture, a driving crank having an eccentric crank portion rotatably mounted in such chamber and operatively connected to said driving shaft, a flanged driving tube pivotally mounted on said crank and having its flange extending into such elongated chamber, and a razor blade reciprocably mounted in such slot between said housing members and pivotally connected to said flanged driving tube and adapted to reciprocate therewith upon rotation of said driving shaft and crank.

5. In a power operated razor, the combination of a housing comprising two bulged members hinged together at the top to form a hollow casing having a longitudinal cylindrical chamber and an elongated chamber, said two members being spaced apart at their lower edge to form a narrow slot, a handle attached to said casing and having a longitudinal aperture in alignment with such cylindrical chamber, a driving shaft rotatably mounted in such handle

- aperture, a driving crank having an eccentric crank portion rotatably mounted in such chamber and operatively connected to said driving shaft, a flanged driving tube 5 pivotally mounted on said crank and having its flange extending into such elongated chamber, a razor blade reciprocably mounted in such slot between said housing members and pivotally connected to said flanged 10 driving tube and adapted to reciprocate therewith upon rotation of said driving shaft and crank, and a guard member attached to one of said housing members and extending adjacent to and below said blade.
- 15 6. In a power operated razor, the combination of a housing comprising two bulged members hinged together at the top to form a hollow casing having a longitudinal cylindrical chamber and an elongated 20 chamber, said two members being spaced apart at their lower edge to form a narrow slot, a handle attached to said casing and having a longitudinal aperture in alignment with such cylindrical chamber, a driving shaft rotatably mounted in such handle aperture, a driving crank having an eccentric crank portion rotatably mounted in such chamber and operatively connected to 25 said driving shaft, a flanged driving tube having an upper tubular portion rotatably mounted on said driving crank in said cylindrical chamber and provided with a downwardly extending flange provided with a 30 series of tubular portions provided with aligned apertures in such elongated chamber, the sides of which act as guideways to obtain a reciprocating motion from said driving tube upon rotation of said crank, a 35 razor blade mounted for reciprocation in the slot between said housing members, and provided at its upper edge in such elongated chamber with tubular portions provided with aligned apertures adapted to fit between the tubular portions on said driving 40 tube, a rod mounted through such apertures in said tubular portions on said razor blade and driving tube to pivotally connect the same so as to reciprocate said blade with 45 said tube, and a guard member attached to one of said housing members and extending below said blade, said guard member terminating in teeth having rounded ends adapted to act as a safety guard for said 50 razor blade.
7. In a power operated razor, the combination of a housing comprising two bulged members hinged together at the top to form a hollow casing having a longitudinal cylindrical chamber and an elongated chamber, said two members being spaced apart at 55 their lower edge to form a narrow slot, a handle attached to said casing and having a longitudinal aperture in alignment with such cylindrical chamber, a driving shaft rotatably mounted in such handle aperture, a driving crank having an eccentric crank portion rotatably mounted in such handle aperture, a driving crank having an eccentric crank portion rotatably mounted in said cylindrical chamber and operatively connected to 60 said driving shaft, a flanged driving tube having an upper tubular portion rotatably mounted on said driving crank in said cylindrical chamber and provided with a downwardly extending flange provided with a 65 series of tubular portions provided with aligned apertures in such elongated chamber, the sides of which act as guideways to obtain a reciprocating motion from said driving tube upon rotation of said crank, a 70 razor blade mounted for reciprocation in the slot between said housing members, and provided at its upper edge in such elongated chamber with tubular portions provided with aligned apertures adapted to fit between the tubular portions on said driving tube, a rod mounted through such apertures in said tubular portions on said razor blade and driving tube to pivotally connect the same so as to reciprocate said blade with 75 said tube, and a guard member attached to one of said housing members and extending below said blade, said guard member terminating in teeth having rounded ends adapted to act as a safety guard for said 80 razor blade.
- Signed by me, this 28th day of February, 1922.
- PAUL SERENE.
